TUBE CAP

Curt P. Frank, Plattsburgh, N. Y.

Application January 7, 1935, Serial No. 770

8 Claims. (Cl. 221—60)

This invention relates to a tube cap and has for an object to provide a new and improved tube cap especially useful on tooth paste tubes or similarly useful on all types of paste tubes including shaving cream, cold cream, paste or any other type of materials that are customarily put up and sold in tubes of this general character.

Previous to this invention many different types of caps have been provided for closing tooth paste tubes, some of them being detachable from the tube and some of them being formed integral with the tube. All of the previous known caps, however, in spite of their many advantages, have certain inherent disadvantages preventing their general adoption. The removable cap has the disadvantage that it is apt to be lost, the integral cap has the disadvantage that it is apt to be too expensive for this type of use and is apt to be too complicated to be practical.

With the cap of this invention, however it is possible to overcome these disadvantages. The cap of this invention is comparatively inexpensive to manufacture yet it can be used continuously on a succession of paste tubes, that is, when one paste tube has been emptied the cap of this invention can be removed therefrom and used on a new tooth paste tube. Once put in position on the tube, however, this cap is not intended to be removed therefrom until the tube has been emptied, whereupon it may be removed and replaced on a new tube. It is placed on the tube by the simplest operation of all, that of merely setting the cap onto the tube, and once in position a simple pressure of the thumb on a thumb piece serves to move the cap to either open or closed position, operating in conjunction with a lock or catch which holds the cap in the open position, while the paste is being dispensed therefrom, and then allows the cap to snap back to the closed position on a slight pressure either of the thumb or on laying the tube down so that a part of the locking means comes into contact with the table on which the tube is being placed.

It is further possible with this invention to lock the cap against accidental opening as when traveling, and to place its part of the locking means out of operation when in ordinary use, as in the home when it may not be desirable, by merely tightening the cap a further half turn on the threaded end of the tube.

With the foregoing and other objects in view, as will hereinafter become apparent, this invention comprises the constructions, combinations and arrangements of parts, hereinafter set forth,

disclosed and shown on the accompanying drawing.

In this drawing,

Figure 1 is a front elevation of the tube cap,
Figure 2 is an end view of the same, looking
from the right in Figure 1,
Figure 3 is a top plan view of the invention,
and

Figure 4 is a sectional view taken on the line
4—4 of Figure 2.

There is shown at 10 a tube of the general nature for which the cap 12 of this invention is used. This tube 10 has the usual threaded neck 11 which is customarily sold with a threaded detachable cap in position thereon. This threaded 15 detachable cap will be discarded and the cap 12 of this invention substituted therefor.

The cap 12 includes a lower jaw 14 to which is hinged an upper jaw 15 by means of a hinged pin 16 about which extends a coil spring 17 having its ends 18 and 19 tending to move the jaws 14 and 15 to the closed position. The lower surface of the lower jaw 14 is generally concave in shape conforming to the convex end 13 of the tube 10. Extending through this lower jaw 14 is a threaded opening 20 which is adapted to be threaded onto the neck 11, the thickness of the lower jaw 14 along the surface of the threads 20 being very slightly less than the length of the threaded neck 11, being less than the length 30 preferably by the thickness of about half a thread. The upper jaw 15 is provided with a cylindrical depression which receives a rubber washer 21 in position opposite the threaded aperture 20 of the lower jaw. The jaws 14 and 15 on the other 35 sides of the pivot pin 16 end in finger grips 22 and 23.

Extending through one of the finger grips, as the upper finger grip 23, is a lock or latching member 24, which consists of a piece of wire 25 J-shaped in outline. The long end of the J 25 ends in a button 26 between the lower side of which and the side of the finger grip 23, is placed a coil expansion spring 27 tending to normally force the button end 26 away from the 45 finger grips 23 and thus draw the short end 28 of the J toward the opposite side of this finger grip 23. This short end 28 extends back through the side 29 of the upper finger grip 23 and this side 29 overlaps a side wall 30 of the lower finger 50 grip 22. This side wall 30 is provided with a pair of spaced locking depressions 31 and 32 connected by an arcuate slightly depressed path 33.

The depressions 31 and 32 are so spaced that when the short end 28 is in the depression 32 55

the jaws are held locked in closed relation to each other, as shown in Figure 4, but when the short end 28 is in the opening 31 the jaws are held locked in open position, as shown in the dot dash outline 15' in Figure 1.

In operation, the cap 12 is substituted for the conventional threaded cap which is discarded. The cap 12 is threaded onto the neck 11 down as far as it will go when intended for use in the home. In this position due to the fact that the thickness of the lower jaw 14 along its threads 20 is slightly less than the threaded end 11 of the tube 10, the upper jaw 15 will not be able to come into full contact with the lower jaw 14 and hence the short end 28 of the locking wire 24 will not enter the locking depression 32.

When in use in the home there is no necessity of locking the jaws in the closed position and the coil spring 17 has sufficient tension to hold the upper jaw 15 and its washer 21 tightly against the edge of the threaded neck 11 and prevent the contents of the tube from being wasted or from drying out.

In order to open the tube and make use of the contents thereof, the finger grips 22 and 23 are grasped or pinched between the fingers pivoting the upper jaw 15 to the position 15' while the short end 28 of locking wire 24 will travel along the arcuate depression 33 and enter the locking depression 31 holding the upper jaw in the position 15' while the contents of the tube are being dispensed. To close the tube thereafter it is only necessary to either manually depress the button 26 or to lay the tube down so that the button 26 comes into contact with the supporting surface allowing the short end 28 of locking wire 24 to be raised out of the locking depression 31 whereby the coil spring 17 will move the upper jaw from the position 15' to the position 15.

When travelling or when carrying the paste tube 10 from place to place it is desirable that the upper jaw 15 be prevented from opening even though other articles in the same container may accidentally press thereagainst. To do this it is only necessary to unthread the cap 12 a half a thread so as to put the upper surface of the lower jaw 14 in the same plane with the edge of the threaded neck 11. This permits the coil spring 17 to close the upper jaw 15 to the fully closed position and allows the short end 28 of locking wire 24 to enter the locking depression 32 and hold the jaws locked in closed position.

When necessary to open the cap 12, it is now necessary to manually depress the button 26 while holding it in depressed condition, squeeze the finger grips 22 and 23 together so as to bring the upper jaw in the position 15 and lock it in that position with the short ends 28 in the locking depression 31.

This invention is thus useful to hold the jaws locked or latched in open position while dispensing the contents of the tube. When used in travelling the jaws may be locked in closed position as when being carried in a handbag preventing the cap from being accidentally opened and dispensing its contents to ruin the other articles in the handbag. When used in the home, however, the means for locking the jaws in closed position may be rendered temporarily inoperative by merely threading the cap by another half turn.

The novel features and the operation of this

device will be apparent from the foregoing description. While the device has been shown and the structure described in detail, it is obvious that this is not to be considered limited to the exact form disclosed and that changes may be made therein within the scope of what is claimed without departing from the spirit of the invention.

Having thus set forth and disclosed the nature of this invention, what is claimed is:

1. A tube cap comprising a pair of jaw members, a pivot securing said jaw members together, a threaded aperture extending through one of said jaw members, and finger grip means integral with said jaw members cooperating with said pivot for pinching said jaw members to open position.

2. A tube cap comprising a pair of jaw members, a pivot securing said jaw members together, one of said jaw members having a threaded aperture extending therethrough from the lower surface thereof to the surface in contact with the other jaw member, means tending to move said jaw members to a closed position, finger grips integral with each jaw member extending to the opposite side of said pivot, said finger grips being spaced from each other when said jaws are in closed position and adapted to be pinched toward each other to move said jaws to open position, and latching means for securing said jaw members in open position.

3. A tube cap comprising a pair of jaw members, a pivot securing said jaw members together, one of said jaw members having a threaded aperture extending therethrough from the lower surface thereof to the surface in contact with the other jaw member, means tending to move said jaw members to a closed position, pinchable means integral with said jaw members cooperating with said pivot for moving said jaw members to an open position, and latching means for securing said jaw members in either open or closed position.

4. A tube cap comprising a pair of jaw members, a pivot securing said jaw members together, one of said jaw members having a threaded aperture extending therethrough from the lower surface thereof to the surface in contact with the other jaw member, means tending to move said jaw members to a closed position, latching means for securing said jaw members in open position, and finger pieces on said jaw members integrally extending to the other side of said pivot for operating said jaw members to open position.

5. A tube cap comprising a pair of jaw members, a pivot securing said jaw members together, one of said jaw members having a threaded aperture extending therethrough from the lower surface thereof to the surface in contact with the other jaw member, means tending to move said jaw members to a closed position, latching means for securing said jaw members in open position, and finger pieces on said jaw members integrally extending to the other side of said pivot for operating said jaw members to open position, said latching means comprising a J-shaped wire having its long end extending through one of said finger pieces and its short end adapted to enter latching depression in the other of said finger pieces, and means normally urging said short end into latching position.

6. A tooth paste tube cap comprising a pair of jaw members, a pivot securing said jaw members together, finger pieces integral with said jaw

- pieces extending on the opposite side of said securing pivot, a coil spring about said securing pivot bearing against said finger pieces urging said jaw members into contacting position, the lower of said jaw members having a threaded aperture extending therethrough from its lower surface to the surface of the other of said jaw members, a washer member countersunk in the other of said jaw members in alignment with said threaded aperture, and means for latching said jaw members in open or closed position. 7. A tooth paste tube cap comprising a pair of jaw members, a pivot securing said jaw members together, finger pieces integral with said jaw pieces extending on the opposite side of said securing pivot, a coil spring about said securing pivot bearing against said finger pieces urging said jaw members into contacting position, the lower of said jaw members having a threaded aperture extending therethrough from its lower surface to the surface of the other of said jaw members, a washer member countersunk in the other of said jaw members in alignment with said threaded aperture, and means for latching said jaw members in open or closed position, said latching means comprising a latch member extending through one of said finger pieces, and a pair of cooperating latch depressions in the other of said finger pieces corresponding to the open and the closed positions thereof. 8. A tooth paste tube cap comprising a pair of jaw members, a pivot securing said jaw members together, finger pieces integral with said jaw pieces extending on the opposite side of said securing pivot, a coil spring about said securing pivot bearing against said finger pieces urging said jaw members into contacting position, the lower of said jaw members having a threaded aperture extending therethrough from its lower surface to the surface of the other of said jaw members, a washer member countersunk in the other of said jaw members in alignment with said threaded aperture, and means for latching said jaw members in open or closed position, said latching means comprising a latch member extending through one of said finger pieces, and a pair of cooperating latch depressions in the other of said finger pieces corresponding to the open and the closed positions thereof, the thickness of said lower jaw member along the threaded aperture therethrough being substantially half a thread less than the length of a threaded tube neck. 25
